UNITED STATES PATENT OFFICE.

LILLIAN M. BENDER, OF SAN FRANCISCO, CALIFORNIA.

FLESH-REDUCING GARMENT.

Application filed May 17, 1922. Serial No. 561,775.

To all whom it may concern:

Be it known that I, LILLIAN M. BENDER, a citizen of the United States, residing in the city and county of San Francisco and State of California, have invented certain new and useful Improvements in Flesh-Reducing Garments, of which the following is a specification.

The present invention relates to that class of garments intended to be worn by those afflicted with obesity for the reduction thereof and consequent improvement in figure and health.

Broadly, the object of the invention is to provide a simple and readily adjustable garment of the character designated of one-piece construction from sheet-rubber, or similar moisture-impervious elastic substance, shaping the same, over a properly prepared mold, to conform in contour to that of the female figure in the abdominal region, and, while on mold, subjecting it to a "baking" process to insure its retaining the form thus obtained.

A further object sought is to improve upon my Patent No. 1,361,220, of December 7, 1920.

With these, and other, ends in view, the invention consists of certain constructional details and adaptations and combinations of component parts of a garment as hereinafter described and more particularly set forth in the claims appended hereto.

In the accompanying drawings, forming a part of this specification, and in which similar reference characters designate like parts, throughout, Figure 1 is a perspective view, showing the garment in position upon a female form and the means for its adjustable securing thereabout.

Figure 2 is a view of the interior of the back portion of the garment; and

Figure 3 is a broken view of the interior surface of the front portion of the garment.

Referring with greater particularity to the drawings, 1 represents the elastic body portion of the garment as molded to conform to the contour of a person's abdomen and hips; 2 the edges of the front opening of the garment to which are secured the means for adjustably securing the garment about

the body; 3 an impervious to moisture flexible flap extending across the front opening of the garment to complete the perfect envelopment of that portion of the body to which it is applied; 4 rubberized fabric strips secured to each edge of the front opening of the garment, and 5 the eyelets therein; 6 rubberized fabric strips vertically disposed on the interior surface of the back portion of the garment; 7 fabric stay pockets sewed, or otherwise secured, onto all of the rubberized strips; 8 rubberized fabric garter tabs cemented to the lower edge of the body portion of the garment; 9 reinforced sections of the body portion of the garment to which the rubberized fabric garter tabs are directly cemented; and 10 extremities of garters in attachment with garter tabs.

In the embodiment of my invention, as herein illustrated, there is shown a garment of the type intended to embrace and compress the body in the abdominal and hip regions, though it is obvious that the garment could be extended to include the brassière feature without in the least departing from the spirit of my invention.

Having thus described my invention, what I claim and desire to secure by Letters Patent as new is:

1. A flesh reducing garment comprising a one-piece body of sheet material molded to conform to the contour of that portion of the body which it is intended to enclose, strips of rubberized fabric material adhesively attached to the body portion and extending vertically thereof, fabric pockets attached to the strips and reinforcing means in said pockets.

2. A flesh reducing garment comprising a one-piece body of sheet material molded to conform to the contour of that portion of the body which it is intended to enclose, strips of rubberized fabric material vulcanized to the body portion and extending vertically thereof, fabric pockets attached to the strips and reinforcing means in said pockets.

3. A flesh reducing garment comprising a one-piece body of sheet rubber adapted to conform to and compress the body of the wearer, said body portion having a vertical

opening extending the entire length thereof, a strip of rubber attached to one edge of the opening and adapted to extend across the opening, rubberized fabric strips adhesively attached to the opposed edges of the opening, eyelet bearing strips secured to said rubberized fabric strips, strips of rubberized fabric material adhesively attached to the body portion of the garment and extending vertically thereof, fabric pockets attached to the last named strips, and reinforcing means in said pockets.

LILLIAN M. BENDER.
